(57) **CLAIM**

I claim the ornamental design for a single headed hammer with interchangeable striking faces, as shown and described.

DESCRIPTION

FIG. 1 is an isometric view of a single headed hammer with six plastic interchangeable faces and six stainless steel interchangeable faces.

FIG. 2 is a front side view thereof, showing exemplary interchangeable faces in place.

FIG. 3 is a right side view thereof, showing exemplary interchangeable faces in place.

FIG. 4 is a top plan view thereof, showing four exemplary interchangeable faces in place; and,

FIG. 5 is a bottom plan view thereof showing four exemplary interchangeable faces in place.

The broken lines depict portions of the striking faces in which the design is embodied that form no part of the claimed design.
